UNITED STATES PATENT OFFICE.

DE VER II. WARNER, OF BRIDGEPORT, CONNECTICUT, ASSIGNOR TO THE WARNER BROTHERS COMPANY, OF SAME PLACE.

DESIGN FOR A HOLDER FOR GARMENT-SUPPORTERS.

SPECIFICATION forming part of Design No. 31,269, dated July 18, 1899.

Application filed November 22, 1898. Serial No. 697,197. Term of patent 14 years.

To all whom it may concern:

Be it known that I, DE VER II. WARNER, a citizen of the United States, residing at Bridgeport, in the county of Fairfield and State of Connecticut, have invented and produced a new and original Design for Holders for Garment-Supporters, of which the following is a specification.

My invention relates to a new and original design for holders for garment-supporters, of which the following is a specification, reference being had to the accompanying drawings.

Figure 1 of the drawings is a plan view of a fastener or holder of a garment-supporter embodying my new design, and Fig. 2 is a sectional edge view of the same.

As shown in the drawings, my new design consists in a holder for a garment-supporter having an upper portion A, provided with a keyhole-slot a, and a lower portion B, provided with a keyhole-slot b, the slots being

arranged one directly below the other, as shown. The exterior edge of my holder is of a generally pandurate configuration.

The leading or material features of my design consist in the two keyhole-slots a and b, one being arranged directly below the other, as shown, with the exterior edge of the holder of a generally pandurate configuration, the lines substantially following the lines of the slots.

What I claim is—

The design for a holder for a garment-supporter, substantially as shown and described.

In testimony whereof I have signed my name to this specification in the presence of two subscribing witnesses.

DE VER II. WARNER.

Witnesses:

FRANK S. ANDREWS,
RUSSELL TOMLINSON.
